US00D681050S

(12) **United States Design Patent**
Ray et al.

(10) **Patent No.:** **US D681,050 S**
(45) **Date of Patent:** **** Apr. 30, 2013**

(54) **DISPLAY SCREEN WITH GRAPHICAL USER INTERFACE**

(75) Inventors: **Ethan Nelson Ray**, Lynnwood, WA (US); **Leslie MacNeil**, Kirkland, WA (US); **Jonathan Eric Gleasman**, Seattle, WA (US); **Denise Michele Trabona**, Seattle, WA (US)

(73) Assignee: **Microsoft Corporation**, Redmond, WA (US)

(**) Term: **14 Years**

(21) Appl. No.: **29/417,170**

(22) Filed: **Mar. 30, 2012**

(57) **CLAIM**

The ornamental design for a display screen with graphical user interface, as shown and described.

DESCRIPTION

FIG. 1 is a front view of a display screen with graphical user interface showing the new design;

FIG. 2 is a front view of a display screen showing an alternative embodiment thereof;

FIG. 3 is a front view of a display screen showing an alternative embodiment thereof; and,

FIG. 4 is a front view of a display screen showing an alternative embodiment thereof.

The broken line showings of the remainder of the user interface and of the tablet computer illustrate unclaimed environment and form no part of the claimed design.

1 Claim, 4 Drawing Sheets
